CLAIM

The ornamental design for a hair dryer holder, as shown and described herein.

DESCRIPTION

FIG. 1 is a perspective view of a hair dryer holder of present invention;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof, and,

FIG. 8 is a exploded perspective view thereof.

The portions of the hair dryer holder shown in broken lines in the drawing are for illustrative purposes only and form no part of the claimed design.
